FOAM DISPENSING UNIT FOR A FLOOR TREATING MACHINE

Frederick G. Cooper, North Muskegon, Mich., assignor
to Clarke Floor Machine Division, Studebaker Corpora-
tion, Muskegon, Mich., a corporation of Michigan

Filed May 16, 1967, Ser. No. 7,149

Term of patent 14 years

(Cl. D37—3)

FIG. 1.

FIG. 2.

FIG. 3.

FIG. 1 is a front-perspective view of a foam dispensing unit for a floor treating machine embodying my novel design;

FIG. 2 is a left side-perspective view thereof;

FIG. 3 is a right side-perspective view thereof;

FIG. 4 is a plan view thereof;

FIG. 5 is a rear-perspective view thereof; and

FIG. 6 is a side-perspective view thereof.

The broken line showing of the machine in FIG. 6 is for illustrative purposes only.

I claim:

The ornamental design for a foam dispensing unit for a floor treating machine, substantially as shown and described.
